UNITED STATES PATENT OFFICE

117,500

DESIGN FOR A BOTTLE

Ovid S. Parker, South Gate, Calif., assignor to Cameo Vinyards Company, Fresno, Calif., a corporation of California

Application September 8, 1939, Serial No. 87,100

Term of patent 14 years

To all whom it may concern:

Be it known that I, Ovid S. Parker, a citizen of the United States, residing at South Gate, in the county of Los Angeles and State of California, have invented a new, original, and ornamental Design for Bottles, of which the following is a specification, reference being had therein to the accompanying drawing, forming part thereof and in which Figs. 1 and 2 are opposite views of a bottle embodying my new design.

I claim:

The ornamental design for a bottle, as shown.

OVID S. PARKER.
